LIGHT DIFFUSING FIXTURE

Lawrence E. Cooke, 11814 Long Leaf, Houston, Tex.

Filed Nov. 23, 1960, Ser. No. 62,940

Term of patent 14 years

(Cl. D48—23)

FIG. 1 is a bottom perspective view of a light diffusing fixture showing my new design.

FIG. 2 is a side elevational thereof as seen from the opposite side of FIG. 1.

The end of the fixture not shown is substantially the same in appearance as the end shown.

The parallel lining on the sides and bottom of the fixture represents surface ornamentation.

The characteristic features of my design for a light diffusing fixture reside in the parallel lined surface ornamentation bordering the edges of the frame in combination with the similar lined surface ornamentation extending between the lenses which have the specific bevelled configuration shown.

What I claim is:

The ornamental design for a light diffusing fixture, substantially as shown and described.
